SHORE ADJUSTING TOOL

Filed March 12, 1928

Inventor:

George B. Bosco.

UNITED STATES PATENT OFFICE

GEORGE B. BOSCO, OF CHICAGO, ILLINOIS

SHORE-ADJUSTING TOOL

Application filed March 12, 1928. Serial No. 260,822.

The main objects of this invention are to provide an improved tool for accurately and quickly adjusting the two struts of a shore; to provide improved means for rigidly securing the tool to one of the struts; to provide a shore adjusting tool which may be readily attached to and removed from the shore so that one such tool may serve a large number of shores; and to provide a device of this kind which is simple in its application and operation so that it may be used by even unskilled labor.

An illustrative embodiment of this invention is shown in the accompanying drawing, 15 wherein:

Figures 1 and 2 are side elevations, partly broken away, showing opposite sides of an adjustable shore to which an improved tool is applied.

Figure 3 is an enlarged perspective of the improved tool, with the wedge removed.

Figure 4 is an enlarged detail in section showing a part of the jack.

In the specific form herein shown, the improved tool involves the use of a fitting adapted to be supported on one of the struts of a shore and having arranged thereon an operating element or jack located in position to engage the other strut for adjusting the two struts longitudinally of each other.

A tool embodying this invention is adapted for use in connection with various forms of overlapping timbers but, in the construction herein illustrated, the tool is applied to a shore comprising telescoping struts 1 and 2.

The strut 1 may be a post of standard form.

The strut 2 comprises a pair of timbers 3 and 4, of different lengths, arranged in substantially parallel spaced relation on a base 5, to which they are connected by straps 6 or other suitable means. Secured to the timbers 3 and 4 and arranged to form one side of the strut 2, is a member 7 which provides a bearing plate on which the post 1 may slide when the shore is used in an inclined position.

The opposite face of the strut 2 is provided with an unobstructed opening 8 between the timbers 3 and 4 through which the workman 50 may insert his hand for gripping the inner

end of the post 1 to obtain the initial rough adjustment of the shore.

The upper ends of the timbers 3 and 4 are rigidly secured to a clamp 9 which is somewhat similar to that shown in my copending application Serial No. 245,469 filed January 9, 1928.

In the form shown, the clamp 9 comprises a pair of side members 10 and 11 arranged in substantially parallel spaced relation and connected together at one end by an angle bar 12 which forms a shelf for engaging the upper extremity of the timber 3. The members 10 and 11 are connected together at the opposite end thereof by end pieces 13 and 14 which engage the outer face of the bar 4. The clamp 9 may be rigidly secured to the bars 3 and 4 by bolts 15.

Formed in the side members 10 and 11 are slots 16 and 17, respectively, of substantially triangular shape to form a keyway for a wedge 18, which is fulcrumed in the outer corners of the slots so as to permit the inner edge of the wedge to swing into and out of engagement with the opposed face of the post 1.

Formed on the side members 10 and 11, adjacent the slots 16 and 17, is a pair of ledges 19 forming bearings for engaging the jack of the adjusting tool.

In the form shown, the improved tool comprises a supporting member in the form of a fitting 20, adopted to embrace the post 1 and on which is mounted an operating element or jack 21. The member 20 is preferably a metal casting shaped for use with rectangular timbers of standard dimensions.

In the form shown, the fitting 20 comprises a pair of spaced yokes 22 and 23, formed on a hollow guide member 24, and arranged to embrace the rectangular post 1.

Formed in the yoke 23 are key slots 25 and 26 for receiving a wedge 27, which is fulcrumed in the outer corners of the slots so as to permit the inner edge of the wedge to swing into and out of engagement with the opposed face of the post 1. The wedge may be fastened to the yoke 23 by a chain 28.

The guide member 24 comprises a hollow

100

post having a pair of oppositely arranged grooves 29.

Formed on the lower end of the post 24, is a housing 30 having an opening 31 in its lower end located in alignment with the bore of the member 24.

10 The operating jack comprises a screw plunger 32 axially movable in the guide member 24 and having pins 33 slidable in the grooves 29 for securing the plunger against rotation relative to the fitting.

15 Mounted on the lower extremity of the plunger 32 is a bearing part 33 adapted to straddle the clamp 9 and to rest on the bearing ledges 19.

Threaded to the plunger 32 is a gear 34 which is positioned between the lower end of the guide 24 and the lower end of the housing 30.

20 Formed on the guide member 24, is a bearing 35, on which is rotatably mounted an operating crank having two handles 36 and 37 provided with a gear part 38 meshing with the gear 34, whereby rotation of the 25 crank effects the desired relative axial movement between the fitting 20 and plunger 32. A screw 39 and washer 40 secure the crank against accidental removal from the bearing 35.

30 In operation, an approximate rough adjustment of the shore is first obtained by lifting the post 1 with the hand and then by means of the wedge 18 the two struts are temporarily secured in their roughly adjusted 35 positions. The fitting 20 is then rigidly secured to the post 1 by means of the wedge 27 and the jack 21 is operated until the bearing part 33 bears firmly against the ledges 19. The wedge 18 of the clamp 9 is then removed 40 from its slots 16 and 17 so as to permit a fine adjustment of the struts. By turning the handles 36 and 37, the fitting 20 and jack 21 are moved relative to each other to effect the desired final adjustment. After the final 45 adjustment is obtained, the wedge 18 is again inserted to lock the struts 1 and 2 together, so as to permit removal of the tool for use on other shores.

I claim:

50 A tool for adjusting a pair of overlapping struts comprising a fitting adapted to embrace one of the struts, means for adjustably securing said fitting to said one strut, a guideway on said fitting, a screw plunger 55 in said guideway and secured against rotation relative to said fitting, said fitting being relatively movable axially of said plunger, a bearing part on said plunger adapted to engage the other strut, and an operating handle 60 mounted on said fitting and geared to said plunger.

Signed at Chicago this 9th day of March, 1928.

GEORGE B. BOSCO.
